CHROMIFEROUS AZO-DYESTUFF AND PROCESS OF MAKING SAME

Fritz Straub, Basel, and Hermann Schneider,
Riehen, near Basel, Switzerland, assignors to
Society of Chemical Industry in Basle, Basel,
Switzerland

No Drawing. Application January 10, 1934, Se-
rial No. 706,148. In Switzerland January 25,
1933

14 Claims. (Cl. 260—12)

The present invention relates to chromiferous azo-dyestuffs. It comprises the process of making these dyestuffs as well as the new dyestuffs themselves.

- 5 5 It has been found that chromiferous azo-dyestuffs are obtained by causing azo-dyestuffs of the general formula

- 10 10 wherein R_1 means a sulfonated naphthalene radical and R_2 a naphthol radical, and wherein the hydroxyl group of the naphthalene radical R_1 stands in ortho-position to the azo-bridge, to re-
15 15 act with agents yielding chromium in such quan-
tities that less than 1 atom of chromium devolves upon each chromable group of the dyestuff mole-
15 15 cule, the reaction being conducted in presence of
soluble salts of organic acids.
- 20 20 Azo-dyestuffs of the above general formula may be obtained from different diazotized ortho-hydroxyaminonaphthalene sulfonic acids by cou-
pling with different naphthols. Diazo compounds of suitable ortho-hydroxyaminonaphthalene sul-
25 25 fonic acids are, for example, the diazo compounds of 1-amino-2-hydroxynaphthalene-4-sulfonic acid, 1-hydroxy-2-aminonaphthalene-4-sulfonic acid, 1-amino-2-hydroxynaphthalene-6-sulfonic acid, 1-amino-2-hydroxynaphthalene-6-chloro-4-
30 30 sulfonic acid, 1-amino-2-hydroxynaphthalene-6-
bromo-4-sulfonic acid; further there may also be used as diazo components for example the nitrated 1-diazo-2-hydroxynaphthalene-4-sul-
35 35 fonic acid and the nitrated 1-diazo-2-hydroxy-
naphthalene-6-sulfonic acid. Suitable coupling components are α - and β -naphthol, as well as their substitution products, such as for example 8-chloro- α -naphthol and 5:8-dichloro- α -naph-
40 40 thol.
- 45 45 The treatment with the agents yielding chro-
mium may take place in an open vessel or under
pressure, in the presence or absence of further
additions, such as, for example, inorganic salts,
organic or inorganic acids, or in neutral or acid
medium.

50 50 As agents yielding chromium there may be used chromium salts, such as, for example, chromium chloride, chromium fluoride, chromium sulfate, chromium sulfite, chromium acetate, chromium
55 55 formate, chromium oxalate, the chromium salt of benzene-sulfonic acid, or mixtures of such chroming agents.

As soluble salts of organic acids in whose presence the treatment with agents yielding chro-
55 55 mium must be carried out in accordance with the present process, there come into considera-
tion, for example, soluble salts of sulfonic acids and carboxylic acids of the aliphatic, aromatic
and hydroaromatic series. Such salts are, for
60 60 example, the alkali metal salts, such as the so-

dium, potassium and ammonium salts of formic acid, acetic acid, propionic acid, oxalic acid, suc-
cinic acid, malonic acid, hexahydrobenzoic acid and hexahydrophthalic acid, or salts of the amino
acids, hydroxy acids, aminohydroxy acids, halo-
genated acids, nitrated acids, so-called exo-acids,
such as ω -benzylsulfonic acids, sulfamic acids,
 ω -methanesulfonic acids, oxamic acids, amino-
mono- and polysulfonic acids of the benzene,
naphthalene and anthracene series, the homo-
logues, analogues and substitution products there-
of, naphthylamine-sulfonic acids, aminonaph-
tholsulfonic acids, arylcarboxylic acids such as
benzoic acids, hydroxybenzoic acids, phthalic
acids and the sulfonic acids thereof, such as sul-
fo-salicylic acids, sulfo-amino-salicylic acids or
sulfo-phthalic acids; particularly valuable re-
sults, however, being obtained with the alkali
metal salts of aliphatic acids.

20 20 The chromiferous azo-dyestuffs obtainable ac-
cording to the present process dye animal fibers,
such as, for example, wool and silk, blue to black
tints. They are considerably superior, with re-
gard to the fastness properties, to the dyestuffs
obtained from the same azo-dyestuffs by treat-
25 25 ment with the same quantities of the same chrom-
ing agent, but in the absence of soluble salts of
organic acids. Dyeing with the dyestuffs obtain-
able according to the present process can be car-
ried out in the usual manner from a sulfuric acid
30 30 bath or from dye baths which, besides inorganic
acids, contain aromatic acids, or advantageously
according to the process described in Patent No.
1,903,884.

35 35 The following examples illustrate the invention,
the parts being by weight:—

Example 1

46.1 parts of the azo dyestuff from nitrated
1-diazo-2-hydroxynaphthalene-4-sulfonic acid 40
and 2-hydroxynaphthalene of the formula

45 45 are stirred in 1000 parts of water. There are 50
then added 4 parts of caustic soda solution of 30
per cent. strength, 12 parts of sodium formate
and a chromium fluoride solution correspond-
ing with 5.32 parts of Cr_2O_3 . The whole is thereupon
boiled for 5 hours in a reflux apparatus, and the 55
black-violet solution thus obtained evaporated
to dryness on the water bath in a vacuum. The
chromiferous dyestuff obtained dyes wool in a
bath containing organic acid and sulfuric acid
black tints of excellent fastness.

5

15

25

30

45

60

Example 2

4,16 parts of the azo-dyestuff from diazotized 2-amino-1-hydroxynaphthalene-4-sulfonic acid and 2-hydroxynaphthalene of the formula

5

10

are dissolved in 100 parts of water containing 0,6 part of caustic soda solution of 30 per cent. strength. A chromium formate solution corresponding with 0,45 part of Cr_2O_3 , and 3 parts of crystallized sodium acetate are added to this solution and the whole is boiled in a reflux apparatus for a long time. The blue solution thus obtained is filtered from small quantities of insoluble impurities, and after concentrating the solution with addition of common salt, the dyestuff is precipitated. The new chromium compound is obtained after drying in the form of a violet-black powder which is easily soluble in water to a reddish-blue solution. In soda solution of 10 per cent. strength, and in dilute caustic soda solution, as well as in concentrated sulfuric acid it dissolves to a greenish blue solution. It dyes wool from a bath containing organic acid and sulfuric acid fast navy blue tints.

Example 3

46,1 parts of the azo-dyestuff from nitrated 1-diazo-2-hydroxynaphthalene-4-sulfonic acid and 2-hydroxynaphthalene of the formula

35

40

45

are suspended in 1000 parts of water. After stirring with 4 parts of caustic soda solution of 30 per cent. strength, there is added a chromium fluoride solution containing 6 parts of Cr_2O_3 , as well as 22,4 parts of sodium lactate and the whole is heated to boiling for a long time in a reflux apparatus. The filtered, brown-violet solution is evaporated to dryness in a vacuum. There is obtained a black powder which is easily soluble in water and dyes wool in a bath containing organic acid and sulfuric acid black tints of excellent fastness properties.

Example 4

46,1 parts of the azo-dyestuff from nitrated 1-diazo-2-hydroxynaphthalene-4-sulfonic acid and 2-hydroxynaphthalene are suspended in 1000 parts of water. After stirring with 4 parts of caustic soda solution of 30 per cent. strength there is added a chromium fluoride solution corresponding with 5,5 parts of Cr_2O_3 , as well as 36 parts of the sodium salt of benzene-sulfonic acid, and the whole is boiled in a reflux apparatus until unchromed dyestuff can no longer be detected. The filtered, violet-black solution is evaporated to dryness in a vacuum. There is obtained a powder which is easily soluble in water and dyes wool in a bath containing organic acid and sulfuric acid black tints of excellent fastness properties.

75

Example 5

46,1 parts of the azo-dyestuff from nitrated 1-diazo-2-hydroxynaphthalene-4-sulfonic acid and 2-hydroxynaphthalene are suspended in 1200 parts of water. After stirring with 4 parts of caustic soda solution of 30 per cent. strength there is added a chromium fluoride solution containing 5,4 parts of Cr_2O_3 , and 46 parts of the sodium salt of naphthalene-1-sulfonic acid, and the whole boiled for 6 to 8 hours in a reflux apparatus. After filtering off small amounts of impurities the solution is evaporated to dryness in a vacuum. The chromiferous dyestuff is obtained as a black powder which is easily soluble in water and dyes wool in a bath containing organic acid and sulfuric acid black tints of excellent fastness properties.

5

10

15

20

25

30

35

46,1 parts of the azo-dyestuff from nitrated 1-diazo-2-hydroxynaphthalene-4-sulfonic acid and 2-hydroxynaphthalene are suspended in 1200 parts of water which contains 4 parts by volume of caustic soda solution of 30 per cent. strength. To this solution there is added a chromium fluoride solution containing 5,6 parts of Cr_2O_3 , as well as 46 parts of the sodium salt of naphthalene-2-sulfonic acid and the whole boiled for 6 to 8 hours in a reflux apparatus. After filtering off small amounts of impurities the solution is evaporated to dryness in a vacuum. The chromium compound which easily dissolves in water to a brown-violet black solution dyes wool in a bath containing organic acid and sulfuric acid black tints of excellent fastness properties.

Example 6

46,1 parts of the azo-dyestuff from nitrated 1-diazo-2-hydroxynaphthalene-4-sulfonic acid and 2-hydroxynaphthalene are suspended in 1500 parts of water which contain 3 parts by volume of caustic soda solution of 30 per cent. strength there are introduced, while stirring, 46,1 parts of the azo-dyestuff from nitrated 1-diazo-2-hydroxynaphthalene-4-sulfonic acid and 2-hydroxynaphthalene. To this solution there are added 50 parts of the sodium salt of 1-amino-naphthalene-5-sulfonic acid and chromium fluoride solution corresponding to 5,8 parts of Cr_2O_3 . The whole is boiled for 6 to 8 hours in a reflux apparatus. The brown-violet black solution thus obtained is then somewhat concentrated, filtered from mineral salts that have precipitated, and evaporated to dryness. The new chromium compound dyes wool in a bath containing organic acid and sulfuric acid black tints of very good fastness properties.

40

45

50

55

41,6 parts of the azo-dyestuff from diazotized 1-amino-2-hydroxynaphthalene-4-sulfonic acid and 1-hydroxynaphthalene of the formula

60

65

are dissolved in 800 parts of water containing 5 parts by volume of caustic soda solution of 30 per cent. strength. To this solution there is added a chromium formate solution containing 5,4 parts of Cr_2O_3 , as well as 21 parts of the sodium salt of phthalic acid, and the whole boiled

75

for 6 to 8 hours in a reflux apparatus. After filtering off small amounts of impurities and evaporating to dryness in a vacuum the chromium compound formed is obtained in the form of a 5 violet black powder. It dissolves freely in water, soda solution of 10 per cent. strength and caustic soda solution of 10 per cent. strength to a blue solution, and in concentrated sulfuric acid to a blue-green solution. The new chromiferous dye-10 stuff dyes wool in a bath containing organic acid and sulfuric acid blue tints of good fastness properties.

Example 9

15 41,6 parts of the azo-dyestuff from diazotized 1-amino-2-hydroxynaphthalene-4-sulfonic acid and 1-hydroxynaphthalene are dissolved in 900 parts of water containing 5 parts by volume of caustic soda solution of 30 per cent. strength. To 20 this solution there is added a chromium lactate solution containing 5,3 parts of Cr_2O_3 , as well as 22 parts of the disodium salt of the 1-amino-4-sulfobenzene-2-carboxylic acid. The whole is boiled for about 6 hours in a reflux apparatus and after filtering off small amounts of impurities 25 the chromium compound formed is isolated by evaporation to dryness in a vacuum. It represents a violet-black powder and dissolves freely in water, soda solution of 10 per cent. strength and caustic soda solution of 10 per cent. strength to a blue solution. In concentrated sulfuric acid 30 it dissolves to a blue-green solution and dyes wool in a bath containing organic acid and sulfuric acid blue tints of good fastness properties.

Example 10

35 49,5 parts of the azo-dyestuff from brominated 1-diazo-2-hydroxynaphthalene-4-sulfonic acid and 1-hydroxynaphthalene of the formula

50 are dissolved in 700 parts of water containing 5 parts by volume of caustic soda solution of 30 per cent. strength. To this solution there is added a 55 solution of the chromium salt of benzene sulfonic acid of about 3 per cent. strength containing 5,5 parts of Cr_2O_3 , as well as 18 parts of sodium formate, and the whole is boiled for 6 to 8 hours in a 60 reflux apparatus. The solution is then evaporated to dryness in a vacuum. The chromium compound which is freely soluble in water to a blue solution dyes wool in a bath containing organic acid and sulfuric acid blue tints of excellent fastness properties.

Example 11

65 49,5 parts of the azo-dyestuff from brominated 1-diazo-2-hydroxynaphthalene-4-sulfonic acid and 2-hydroxynaphthalene of the formula

75 are dissolved in 1000 parts of water containing 6 parts by volume of caustic soda solution of 30

per cent. strength. To this solution there are added 40,8 parts of sodium acetate, as well as a chromium solution containing 4,5 parts of Cr_2O_3 , 2 parts of hydrofluoric acid, and 5 parts of formic acid of 85 per cent. strength, and the whole is heated for 3-4 hours to 120° C. After filtering off small amounts of impurities the blue solution obtained is concentrated and the chromiferous dyestuff precipitated by addition of common salt. The chromium compound which is freely soluble in water dyes wool in a bath containing organic acid and sulfuric acid blue tints of excellent fastness properties.

Example 12

15 4,16 parts of the azo-dyestuff from diazotized 2 - amino-1-hydroxynaphthalene-4-sulfonic acid and 2-hydroxynaphthalene of the formula

are dissolved in 100 parts of water and 2 parts of caustic soda solution of 10 per cent. strength. To this solution there are added chromium formate corresponding with 0,42 part of Cr_2O_3 as well as 4 parts of the disodium salt of 1-hydroxy-4-sulfobenzene-2-carboxylic acid. The whole is boiled for a long time in a reflux apparatus. The blue solution which has formed is concentrated, if necessary after filtering off small amounts of impurities, and the dyestuff precipitated by addition of common salt. There is obtained a violet-black powder which dissolves in water to a reddish, blue solution and dyes wool in a bath containing organic acid and sulfuric acid navy blue tints of good fastness properties.

Example 13

45 46,1 parts of the azo-dyestuff from nitrated 1-diazo-2-hydroxynaphthalene-4-sulfonic acid and 1-hydroxynaphthalene of the formula

are dissolved in 1000 parts of water with addition of 5 parts by volume of caustic solution of 30 per cent. strength. To this solution there is added a 60 solution of chromium formate containing 5,3 parts of Cr_2O_3 , as well as 20 parts of sodium formate, and the whole is boiled for 6 to 8 hours in a 65 reflux apparatus. The violet-black solution of the chromium compound which has formed is evaporated to dryness in a vacuum, if necessary after filtering off small amounts of impurities. There is obtained a black powder which dissolves in water to a violet-black solution, and in soda solution of 10 per cent. strength and caustic soda solution of 10 per cent. strength to a brown-violet black solution. The new dyestuff dissolves in concentrated sulfuric acid to a green black solution. It dyes wool and silk in a bath containing organic 70-75

acid and sulfuric acid black tints of good fastness properties.

Example 14

- 35 41.6 parts of the azo-dyestuff from diazotized 1-amino-2-hydroxynaphthalene-4-sulfonic acid and 1-hydroxynaphthalene are dissolved in 7 parts by volume of caustic soda solution of 30 per cent. strength and 1000 parts of water. To this solution there is added a chromium fluoride solution containing 5.4 parts of Cr_2O_3 , as well as 20 parts of sodium formate, and the whole is boiled for 6 hours in a reflux apparatus. The blackish-blue solution which has formed is evaporated to dryness in a vacuum, if necessary after filtering off small quantities of impurities. There is obtained a violet-black powder which freely dissolves in water, soda solution of 10 per cent. strength and caustic soda solution of 10 per cent. strength to a blue solution, and in concentrated sulfuric acid to a blackish blue-green solution. The new chromiferous dyestuff dyes wool in a bath containing organic acid and sulfuric acid blue to navy blue tints of very good fastness properties.

25

Example 15

- 35 83.2 parts of the azo-dyestuff from diazotized 1-amino-2-hydroxynaphthalene-4-sulfonic acid and 2-hydroxynaphthalene of the formula

- 40 are suspended in a pressure vessel in 1200 parts of water. To this suspension there are added 10 parts by volume of caustic soda solution of 30 per cent. strength, 30 parts of sodium formate, as well as a chromium formate solution corresponding with 8 parts of Cr_2O_3 , and the whole is heated 45 to 120 to 130° C. for 3 to 4 hours. After cooling, small amounts of impurities are filtered off and the blackish blue solution is evaporated to dryness in a vacuum, a violet-black powder being obtained. The chromium compound which is freely soluble 50 in water to a reddish blue, red dichroic solution dissolves also in soda solution of 10 per cent. strength and in caustic soda solution of 10 per cent. strength to a reddish blue solution, whereas in concentrated sulfuric acid it dissolves to a 55 greenish blue solution. The new dyestuff dyes wool in a bath containing organic acid and sulfuric acid fast navy blue tints.

What we claim is:—

- 60 1. Process for the manufacture of chromiferous azo-dyestuffs, consisting in causing azo-dyestuffs of the general formula

65

- wherein R_1 means a sulfonated naphthalene radical and R_2 a naphthol radical, and wherein the hydroxyl group of the naphthalene radical R_1 stands in ortho-position to the azo-bridge, to react with agents yielding chromium in such a proportion as to provide less than one atom of chromium to each chromable group of the dyestuff molecule, the reaction being conducted in presence of soluble salts of organic acids.

- 75 2. Process for the manufacture of chromiferous

azos dyestuffs, consisting in causing azo-dyestuffs of the general formula

wherein R_1 means a sulfonated naphthalene radical and R_2 a naphthol radical, and wherein the hydroxyl group of the naphthalene radical R_1 stands in ortho-position to the azo-bridge, to react with agents yielding chromium in such a proportion as to provide less than one atom of chromium to each chromable group of the dyestuff molecule, the reaction being conducted in presence of alkali metal salts of aliphatic acids.

3. Process for the manufacture of chromiferous azo-dyestuffs, consisting in causing the azo-dyestuff of the general formula

wherein R_1 means a sulfonated naphthalene radical and the hydroxyl group of the naphthalene radical R_1 stands in ortho-position to the azo-bridge, to react with agents yielding chromium in such a proportion as to provide less than one atom of chromium to each chromable group of the dyestuff molecule, the reaction being conducted in presence of alkali metal salts of aliphatic acids.

4. Process for the manufacture of chromiferous azo-dyestuffs, consisting in causing the azo-dyestuff of the formula

to react with agents yielding chromium in such a proportion as to provide less than one atom of chromium to each chromable group of the dyestuff molecule, the reaction being conducted in presence of alkali metal salts of aliphatic acids.

5. Process for the manufacture of chromiferous azo-dyestuffs, consisting in causing the azo-dyestuff of the formula

to react with agents yielding chromium in such a proportion as to provide less than one atom of chromium to each chromable group of the dyestuff molecule, the reaction being conducted in presence of alkali metal salts of aliphatic acids.

6. Process for the manufacture of a chromiferous azo-dyestuff, consisting in causing the azo-dyestuff of the formula

to react with agents yielding chromium in such a

proportion as to provide less than one atom of chromium to each chromable group of the dyestuff molecule, the reaction being conducted in presence of sodium formate.

5 7. Process for the manufacture of a chromiferous azo-dyestuff, consisting in causing the azo-dyestuff of the formula

15 to react with agents yielding chromium in such a proportion as to provide less than one atom of chromium to each chromable group of the dyestuff molecule, the reaction being conducted in presence of sodium formate.

20 8. Chromiferous azo-dyestuffs obtained by causing azo-dyestuffs of the general formula

25 wherein R_1 means a sulfonated naphthalene radical and R_2 a naphthol radical, and wherein the hydroxyl group of the naphthalene radical R_1 stands in ortho-position to the azo-bridge, to react with agents yielding chromium in such a proportion as to provide less than one atom of chromium to each chromable group of the dyestuff molecule, the reaction being conducted in presence of soluble salts of organic acids which products represent black powders dissolving in water to blue to black solutions and dyeing animal fibers fast blue to black tints.

30 9. Chromiferous azo-dyestuffs obtained by causing azo-dyestuffs of the general formula

40 wherein R_1 means a sulfonated naphthalene radical and R_2 a naphthol radical, and wherein the hydroxyl group of the naphthalene radical R_1 stands in ortho-position to the azo-bridge, to react with agents yielding chromium in such a proportion as to provide less than one atom of chromium to each chromable group of the dyestuff molecule, the reaction being conducted in presence of alkali metal salts of aliphatic acids which products represent black powders dissolving in water to blue to black solutions and dyeing animal fibers fast blue to black tints.

45 10. Chromiferous azo-dyestuffs obtained by causing azo-dyestuffs of the general formula

60 wherein R_1 means a sulfonated naphthalene radical and the hydroxyl group of the naphthalene radical R_1 stands in ortho-position to the azo-bridge, to react with agents yielding chromium in such a proportion as to provide less than one atom of chromium to each chromable group of the dyestuff molecule, the reaction being conducted in presence of alkali metal salts of aliphatic acids, which products represent black powders dissolving in water to blue to black solutions

and dyeing animal fibers fast blue to black tints.

65 11. Chromiferous azo-dyestuffs obtained by causing the azo-dyestuff of the general formula

80 to react with agents yielding chromium in such a proportion as to provide less than one atom of chromium to each chromable group of the dyestuff molecule, the reaction being conducted in presence of alkali metal salts of aliphatic acids, which products represent black powders dissolving in water to black solutions and dyeing wool fast black tints.

85 12. Chromiferous azo-dyestuffs obtained by causing the azo-dyestuff of the formula

100 to react with agents yielding chromium in such a proportion as to provide less than one atom of chromium to each chromable group of the dyestuff molecule, the reaction being conducted in presence of alkali metal salts of aliphatic acids, which products represent black powders dissolving in water to blue solutions and dyeing wool fast blue to navy blue tints.

105 13. A chromiferous azo-dyestuff obtained by causing the azo-dyestuff of the formula

120 to react with agents yielding chromium in such a proportion as to provide less than one atom of chromium to each chromable group of the dyestuff molecule, the reaction being conducted in presence of sodium formate, which product represents a black powder dissolving in water to a black solution and dyeing wool fast black tints.

125 14. A chromiferous azo-dyestuff obtained by causing the azo-dyestuff of the formula

140 to react with agents yielding chromium in such a proportion as to provide less than one atom of chromium to each chromable group of the dyestuff molecule, the reaction being conducted in presence of sodium formate, which product represents a black powder, dissolving in water to a blue solution and dyeing wool fast blue to navy blue tints.
